The ornamental design for a universal cluster tie down strap,
as shown and described.

DESCRIPTION

FIG. 1 is a front elevational view of a universal cluster tie
down strap showing my new design;

FIG. 2 is a rear elevational view thereof;

FIG. 3 is a right side view thereof;

FIG. 4 is a left side view thereof;

FIG. 5 is a bottom view thereof; and,

FIG. 6 is a top view of the invention.

It is understood that the irregular break lines in the claimed
design are shown to indicate indeterminate length.
